By Cheever & Cox Atty's.

UNITED STATES PATENT OFFICE.

JOHN LOFGREN, OF CHICAGO, ILLINOIS, ASSIGNOR TO RALCO MANUFACTURING COMPANY, OF CHICAGO, ILLINOIS, A CORPORATION OF ILLINOIS.

ELECTRIC SWITCH.

Application filed November 2, 1925. Serial No. 68,142.

REISSUED

My invention relates to switches, especially of the type enclosed within a housing or casing and of heavy construction so that it may be employed on locomotives and in other situations where the device will be subjected to an unusual amount of vibration and to rough usage. The general object of the invention is to provide a simple and practical switch having the characteristics mentioned. Another object is to provide a construction in which the chief operating elements of the switch are enclosed within a housing and the operating handle is mounted on the housing cover, and the parts are so constructed that the handle will connect with and disconnect from the switch operating part merely by placing or removing the cover. Another object is to make allowances for minor discrepancies of manufacture so that the switch handle will take hold of the rotor when the cover is applied, even though the parts are somewhat irregular in construction or position. Another object is to provide means whereby the stationary terminals may be grouped in various ways to produce different effects when the rotor is rotated. Still another object is to provide means for insuring good electric contact between the rotor and its supply conductor, and also to provide convenient means for holding the rotor contacts in proper alignment with the stationary terminals.

I obtain my objects by the mechanism illustrated in the accompanying drawings, in which

Figure 1 is a perspective view of the complete device.

Figure 2 is a sectional view on the line 2—2 Figure 1.

Figure 3 is a front view of the device with the housing cover removed for revealing the internal mechanism.

Figure 4 is a sectional view on the line 4—4 Figure 3.

Figure 5 is a perspective view of the terminal base block.

Figure 6 is a perspective view of the operating handle.

Figure 7 is a perspective view of the main elements of the rotor.

Figure 8 is a perspective view of the terminal bar and associated parts.

Figure 9 is a fragmentary view of the back side of the base block, showing the terminal bar and associated parts.

55

Like numerals denote like parts throughout the several views.

According to the design selected to illustrate the invention, the chief operating parts are located within a housing 10 provided with a cover 12, which may be bolted or otherwise removably secured in place. Fastened within the housing by means of studs 14 or other appropriate means is a base block 16 of insulating material. Between the block and the housing is a plate 18, which is also of insulating material.

The block 16, which is shown in perspective in Figure 5, is here shown to be circular in outline and provided with a number of notches 20 in its front face adjacent to the circumference. At the center it has an aperture 22. The notches 20 form seats for stationary terminals 24 which are provided with binding posts 26. These terminals 75 form the stationary contacts and project radially inward towards the axis of the block. In the drawings I have shown three stationary terminals but more than three notches, the idea being to provide for an increased number of terminals or a different grouping thereof should occasion require.

80 A terminal bar 28 of conductive material is fastened by screws 30 or otherwise to base block 16 in the manner best shown in Figures 2, 3 and 4. This bar is provided with a binding post 32 at one end and with an aperture 34 at the other end, as shown in perspective in Figure 8. It is arranged radially with reference to the base block and 90 seats within a channel 36 formed therein as best shown in Figure 5.

85 Adjacent to the bar 28 is a leaf spring 38 which is secured at the outer end to the front of the bar and at the inner end has an aperture 40 coaxial with the aperture 34 in bar 28. This spring presses forward 95 against one of the plates 50, hereinafter mentioned, and serves the double purpose of carrying current to it from bar 28 and 100

also of preventing rattling of the parts. The apertures 34 and 40 are for accommodating a stud 42 which is journaled in bar 28 and has a stop pin 44 for abutting the rear 6 surface of bar 28 and thus limiting the distance to which the stud may be forced forward toward the front of the device. The amount of rotation of the stud is limited by a pin 46 fastened to bar 28 and projecting 10 backwards therefrom into the path of pin 44. Thus the stud may be rotated back and forth but cannot revolve more than about 180 degrees, as pin 46 projects in both directions from the stud. Pin 44 also holds 15 the rotor in place when the cover is removed.

Stud 42 is shouldered and riveted at the forward end in such manner as to firmly hold a disc 48 in the manner best shown in Figure 2. Riveted to this disc, one on 20 each side thereof, are plates 50 having sectors 52 arranged in two pairs and projecting approximately in opposite directions from the disc. These sectors form jaws or contacts for engaging between them the terminals 24, 25, 27. It will be evident that these 25 sectors or contacts 52 are rotatable and constitute two of the principal portions of the rotary element of the switch or "rotor".

Projecting forward from the disc 48 and 30 plates 50 are two shouldered pins 54 which serve to hold an insulating block 56 in the manner best shown in Figure 2. The block is held loosely so that it may shift its position to a very slight extent to take care of 35 inaccuracies of manufacture and to facilitate engagement with the operating shaft 58. Said shaft is journaled in the front cover 12 and is bifurcated at its inner end to fit over block 56. By preference the central slot 60 of the shaft is somewhat wider 40 than block 56 so that the block may readily enter the slot when the cover is being applied.

Extending radially from the outer end of 45 the shaft is an operating handle 62 which is of ample proportions and rugged so that it may withstand a considerable amount of abuse. On the inner side it has a spring-pressed ball 64 adapted to travel over a 50 quadrant 66 having notches 68 for yieldingly holding the arm 62 in various positions. Heavy lugs 70 are cast integral with the cover 12 at the ends of the quadrant for 55 limiting the swing of the operating handle. These form positive, rugged stops for limiting the angular movement of the handle.

In practice, when the base block 16, stationary terminals 24, and the rotor are 60 mounted within the housing 10, as illustrated, the operating handle 62 is brought into and out of engagement with the block 56 of the rotor by merely applying the cover 12 to the housing and rotating the arm to such position as to fit over block 56. The 65 slotted shaft 60 may be regarded as a clutch

which is detachable from the rotor by moving it away in an axial direction. This forms a practical expedient which simplifies manufacture as well as simplifying the operation. By removing the cover and attached handle the operating parts of the switch are completely exposed.

To operate, the handle 62 is rotated in one direction or the other. When used as a locomotive headlight the contacts 52 of the 70 rotor and the terminals 24, 25, 27 will usually be so arranged that when the handle is in central position as shown in Figure 1 the contacts 52 will be out of engagement with any of the terminals, and both locomotive 80 headlights will be off. By rotating the handle to the next notch at the right the front headlight will be dim, and by rotating the handle to the extreme right the front headlight will receive full voltage. By rotating the handle to the left of central position the rear headlight will be controlled in the same manner. Thus the switch gives the locomotive engineer full control of both headlights.

It will be understood that my device is not limited for use as a locomotive headlight switch. The base block 16, being provided with a considerable number of notches 20, is of course capable of supporting an equal 90 number of stationary terminals 24. The consequence is that by altering the number and arrangement of terminals 24 and contacts 52 various arrangements of circuits may be provided for.

Having thus described my invention what 100 I claim as new and desire to secure by Letters Patent is:

1. A switch having a stationary terminal, a rotary switch blade for engaging and disengaging it, a stud on which said blade is 105 mounted, a supporting element for the stud, a spring pressing against the switch blade in an axial direction for preventing rattling, a stop on the stud engaging said supporting element for limiting the movement of the stud to thereby hold the switch plate in alignment with the stationary terminal, and means for energizing said spring to thereby 110 energize the switch blade.

2. A switch having a stationary terminal, 115 a rotary switch blade for engaging and disengaging it, a stud on which said blade is mounted, a supporting element for the stud, a spring pressing against the switch blade in an axial direction for preventing rattling, and a stop pin projecting from the side of the stud for serving the dual purpose of 120 limiting the axial movement of the stud under the pressure of the spring and for limiting the angular movement of the stud.

3. A switch having stationary terminals adapted to be variously grouped, a rotary 125 switch element for engaging said terminals, a base on which the terminals are mounted, a spring pressing against the switch element 130

for energizing it and preventing rattling, an insulating block for rotating the switch element, a handle fitting over the block for engaging and rotating it, a pin passing radially through the stud in both directions, and a stationary stop adapted to be engaged by said pin for limiting the rotation of the block to less than 180 degrees, to establish

the position which the block must occupy to be engaged by the handle, said pin also limiting the distance to which the stud may be moved axially under the force of the spring.

In witness whereof, I have hereunto subscribed my name.

JOHN LOFGREN.
